UNITED STATES PATENT OFFICE.

JOHN J. DE LANCEY, OF BINGHAMTON, NEW YORK.

BALANCED SLIDE-VALVE.

SPECIFICATION forming part of Letters Patent No. 284,395, dated September 4, 1883.

Application filed June 5, 1883. (No model.)

To all whom it may concern:

Be it known that I, JOHN J. DE LANCEY, of Binghamton, in the county of Broome and State of New York, have invented a new and Improved Balanced Slide-Valve, of which the following is a full, clear, and exact description.

My invention relates to that class of slide-valves that are fitted to work beneath a face-plate placed in the steam-chest, as shown in the Letters Patent granted to me June 20, 1876, No. 179,002, reissued June 27, 1882, and No. 261,688, dated July 25, 1882.

Reference is to be had to the accompanying drawings, forming a part of this specification, in which similar letters of reference indicate corresponding parts in all the figures.

Figure 1 is a plan view of my improved valve arrangements as contained in a steam-chest, the cover being removed. Fig. 2 is a plan view with the face-plate removed from the chest, showing the upper side of the balance-plate. Fig. 3 is a plan view of the valve, both the face-plate and the balance-plate being removed. Fig. 4 is a cross-section of the steam-chest and valve. Fig. 5 is an inverted plan view of the balance-plate.

The valve A is of rectangular form, open top and bottom, and is fitted upon its outside with packing-bars *a*, set in grooves. The face-plate B fits closely in the steam-chest, with the exception of openings *b* at the corners and openings *c c* at opposite sides of the steam-chest, which are provided to allow free circulation of oil and steam. This plate is supported by rests cast upon its under side, that take upon the valve-seat; or they may be supported by lugs cast upon the inner surface of the chest.

The parts above described are substantially as shown in the Letters Patent aforesaid.

D is the balance-plate, resting upon the packing-bars *a* of the valve, and formed with flanges upon its under side, that fit within the top of the valve, so that the plate shall be moved with and by the valve. The upper surface of the balance-plate is formed with grooves or countersinks *e*, extending around the plate at

a distance from its edges about the width of the packing-bars *a* beneath. These grooves or countersinks *e* are connected by cross-grooves with the central aperture, *f*, at the center of the plate, so that the countersinks are connected to the exhaust-cavity of the valve. The object of this construction is for the purpose of balancing the pressure, and for conducting the steam that may leak past the outer edges of the balance-plate to the exhaust. The groove will also serve for the admission of exhaust-steam and oil between the upper side of the balance-plate and the under side of the face-plate. By using these countersinks I obtain a wearing-surface around the aperture *f* that is without pressure or friction, and the oil being conducted by the grooves *e* to the under side of the face-plate, no oil-hole is required in the center of the plate *B*. At the ends of the balance-plate *D* are grooves *i i* for the admission of steam between the two plates for lubricating the portion not covered by the grooves *e* in the movement of the valve. In this manner the steam and oil is passed over the whole wearing-surface between the face-plate and the balance-plate at every movement of the valve, either forward or back.

At *k* upon the cover of the steam-chest is a valve for the admission of air when the engine is running without steam. The projections *l* upon the face-plate are for receiving the ends of set-screws for holding the plate down to its position.

Having thus described my invention, I claim as new and desire to secure by Letters Patent—

The balance-plate *D*, having a central aperture, and formed on its upper side with wearing-surfaces separated by grooves or countersinks *e*, that are connected to the central aperture, in combination with the face-plate *B* and the slide-valve *A*, having packing-bars *a*, substantially as described.

JOHN J. DE LANCEY.
